(57) **CLAIM**

The ornamental design for an audio and video module display attachment for the front of a beverage dispenser fountain head, as shown and described.

DESCRIPTION

FIG. 1 is a perspective view of an audio and video module display attachment for the front of a beverage dispenser fountain head showing my new design;

FIG. 2 is a rear view thereof, with the mounting bracket removed for ease of illustration;

FIG. 3 is a rear elevational view thereof including the mounting bracket attached;

FIG. 4 is a left side elevational view thereof including the mounting bracket attached;

FIG. 5 is a front elevational view thereof with the mounting brackets removed for ease of illustration;

FIG. 6 is a top plan view thereof, including the mounting brackets;

FIG. 7 is a bottom plan view thereof; and,

FIG. 8 is a right side elevation view thereof, with mounting brackets installed.

The broken line showing of a beverage fountain dispenser head is for the purpose of illustrating the environment where the device is used and forms no part of the claimed design.

The broken line showing of mechanical and electrical inputs on the rear of the device is for the purpose of illustrating said inputs and forms no part of the claimed design.
